UNITED STATES PATENT OFFICE

ROSS T. CRUIKSHANK, OF MINNEAPOLIS, MINNESOTA

PUMP JACK

Application filed June 7, 1929. Serial No. 369,230.

My invention relates to pump jacks, and an object is to provide a device of this class which may be readily installed for efficient application of power in order to operate 5 pumps. It has been customary heretofore to operate pumps by means of a walking beam construction. In carrying out my invention, I provide a cam construction in combination with a reciprocating slide which causes pump 10 links attached thereto to move up and down without any rocking movement.

The full objects and advantages of my invention will appear in connection with the detailed description thereof, and the novel 15 features of my inventive idea will be particularly pointed out in the claims.

In the accompanying drawings which illustrate my invention in one of the forms in which it may be embodied,—

20 Fig. 1 is a view of the device mostly in central vertical section. Fig. 2 is a view in horizontal section on the line 2—2 of Fig. 1. Fig. 3 is a view in central vertical section taken at right angles to Fig. 1. Fig. 4 is a 25 view of a cam on a reduced scale.

As shown in the drawings, the support of 30 the device includes a horizontal plate 10, one side of which is rounded as indicated at 12 in Fig. 2 and is provided with a leg 14 having an 35 outturned foot 16 by which it may be anchored. A vertically disposed guide member 18 is provided with horizontal flanges 20 intermediate its length which are secured to the opposite side of the plate 10 by bolts or rivets 40 22. The guide member 18 is downwardly extended to form legs 24 having feet 26 which may be anchored and this guide member is provided with a vertical slot 28 which receives a slide 30. The slide 30 is held for reciprocation in the slot 28 by a rear plate 32 and a front plate 34, these plates being held to the slide by a lower bolt 36 and an upper bolt 38. The rear portion of the bolt 38 is extended and constitutes an enlargement 45 upon which a roller 42 is mounted. The plate 10 carries bearings 44 and 46 for a shaft 48 to the outer end of which a driving pulley 50 is secured. A bevel gear 52 secured to the shaft 48 projects up through a slot 54 in the 50 plate 10 and meshes with an annular bevel

gear 56 which preferably forms part of a casting having a horizontal disk member 58 provided with a hub 60. The annular gear 56 extends down from the disk member 58 while an annular cam 62 extends up from the disk member 58, this cam being so positioned that as it is rotated, the roller 42 is in engagement with the upper margin thereof. By referring to Fig. 4, it will be understood that the margin of the cam consists of a downward 55 inclination 64 and an upward inclination 66, the latter inclination being much longer than the other inclination. A bolt 68 passing through the hub 60 and through the plate 10 serves to hold the combined gear and cam member in place for rotative movement. The lower end of the plate 34 is turned forwardly to provide two lugs 70 and 72 to which the lower end of pump links 74 and 76 are secured respectively by bolts 78 and 80. The 60 upper ends of the links 74 and 76 are connected by a cross bar 82 whose central portion carries two spaced lugs 84 and 86 between which the upper end of a pump rod 88 is placed and secured by a bolt 90. The 65 pump rod 88 operates in the usual manner in connection with a pump, parts of which are indicated at 92 and 94 in Fig. 1.

The operation and advantages of my invention will now be obvious. The construction provides a slow lift with long leverage and with a quick drop. The slide 30 is constrained to move up and down in the guide member and hence the pump links 74 and 76 move up and down without rocking movement, thereby avoiding wear which would be caused by such movement. It will be understood that the contour of the cam will be such as to give the desired ratio between the lifting and return strokes. By referring to 80 Fig. 3, it will be understood that the slot 28 extends both above and below the plate 10 whereby the movement of the slide is across the plane of the plate.

I claim:

1. A pump jack comprising a horizontal supporting plate, a vertically disposed guide member having horizontal flanges secured to said plate, said guide member being downwardly extended to form legs and contain-

- ing a vertical slot, a slide working in said slot, front and rear plates for holding said slide in said slot, bolts passing through said plates and slide, one of said bolts being extended and carrying a roller, a disk member rotatably mounted on said supporting plate by a vertical pivot, an annular cam extending up from said disk member and engaged by said roller, an annular gear extending down from said disk member, a shaft rotatably mounted below said annular gear, a pinion secured to said shaft and meshing with said annular gear, a driving pulley secured to the outer end of said shaft, and pump links attached to said slide.
15. 2. A pump jack comprising a horizontal supporting plate, a vertically disposed guide member secured to said plate and containing a vertical slot, a slide working in said slot, front and rear plates for holding said slide in said slot, bolts passing through said plates and slide, one of said bolts being extended and carrying a roller, a disk member rotatably mounted on said supporting plate by a vertical pivot, an annular cam extending up from said disk member and engaged by said roller, an annular gear extending down from said disk member, a shaft rotatably mounted below said annular gear, a pinion secured to said shaft and meshing with said annular gear, a driving pulley secured to the outer end of said shaft, and pump links attached to said slide.
20. 3. A pump jack comprising a horizontal supporting plate, a vertically disposed guide member secured to said plate, a slide held for reciprocation on said guide, a roller extending out from said slide, a disk member rotatably mounted on said supporting plate by a vertical pivot, an annular cam extending up from said disk member and engaged by said roller, an annular gear extending down from said disk member, a shaft rotatably mounted below said annular gear, a pinion secured to said shaft and meshing with said annular gear, a driving pulley secured to the outer end of said shaft, and pump links attached to said slide.
25. 4. In testimony whereof I hereunto affix my signature.

50 ROSS T. CRUIKSHANK.
